UNITED STATES PATENT OFFICE.

JACQUES SCHNEIDER AND FREDERIC BILLON, OF SOLOTHURN, AND ERNST HURLIMANN, OF ZUCHWIL, SWITZERLAND, ASSIGNEES TO THE FIRM SCINTILLA, SOLOTHURN, SWITZERLAND.

INTERRUPTER IN IGNITION APPARATUS FOR INTERNAL-COMBUSTION ENGINES.

Application filed August 22, 1919. Serial No. 319,229.

To all whom it may concern:

Be it known that we, JACQUES SCHNEIDER, a citizen of the Swiss Republic, residing at Solothurn, Switzerland, FREDERIC BILLON, a citizen of the Swiss Republic, residing at Solothurn, Switzerland, and ERNST HURLIMANN, a citizen of the Swiss Republic, residing at Zuchwil (Canton of Solothurn), Switzerland, have invented certain new and useful Improvements in Interrupters in Ignition Apparatus for Internal-Combustion Engines, of which the following is a specification.

This invention provides an improved construction of the interrupter in ignition apparatus for internal combustion engines, which allows of employing the improved interrupter for both directions of rotation in the running of the ignition apparatus without having to replace any parts by others.

In order to effect this, parts of the improved interrupter including the main supporting casing, the insulated fixed contact holder, the cam plate and the stub axle on which the movable interrupter lever rocks are made symmetrical to a plane passing vertically through the axis of rotation, whilst the interrupter lever with its spring, spring fixing screw and both fixed and movable contacts are made symmetrical to a vertical plane at right angles to the first mentioned plane.

The accompanying drawings illustrate a constructional example of the improved interrupter with a rotating cam plate and stationary contacts.

Fig. 1 shows the arrangement for running in the right hand direction. Fig. 2 shows the arrangement for running in the left hand direction, and Fig. 3 is a plan of the interrupter contacts.

As shown, the cam plate *b*, the interrupter

casing *c* with the contact holder *d* for carrying the stationary interrupter contact *h*, 45 and the stub axle *e* for the interrupter lever *f*, are made symmetrical to the vertical plane *X*—*X* passing through the axis *a* of the apparatus, whilst the interrupter lever *f* with the movable contact *g*, the stationary contact *h* and the spring *i*, are made symmetrical to the plane *Y*—*Y* shown in Fig. 3. The contact holder *d* is formed with lugs *k* on each side and is insulated from the main casing *c* by the non-conducting layer *m*. The 55 casing *c* is provided on both sides with screw-threaded holes for the attachment of the spring *i*.

What we claim is:—

A circuit breaker for the primary winding 60 of a magneto arranged to allow of operation in both directions of rotation, including a main supporting case symmetrical about a vertical plane, a rotary cam adapted to rock a pivoted lever carrying a contact, two 65 symmetrically disposed seatings carried on said main case and insulated therefrom, a second contact adapted to be fitted to either of said seatings at will and coacting with the first mentioned contact in such a manner 70 that the point of contact is in a definite position in the said vertical plane for both directions of rotation, a spring attached at one end to said pivoted lever and at its other end to one of a pair of symmetrical seatings 75 on the main supporting case, and a single pivot on which the said pivoted lever rocks for both directions of rotation of the cam, said pivot being fixed to the main casing in the said vertical plane of symmetry. 80

In testimony whereof we have signed our names to this specification.

JACQUES SCHNEIDER,
ERNST HURLIMANN.
FREDERIC BILLON
